(57) **CLAIM**

We claim, the ornamental design for an inlet for vacuum cleaner, as shown and described.

DESCRIPTION

FIG. 1 is a perspective view of an inlet for vacuum cleaner, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another right side elevation view in an alternate position; and,

FIG. 9 is another right side elevation view thereof with an unclaimed brush attachment.

The broken lines illustrating portions of the inlet for vacuum cleaner are for environmental purposes only and form no part of the claimed design.
